UNITED STATES PATENT OFFICE

150,687

DESIGN FOR A MICROPHONE OR THE LIKE

Joseph B. Federico, New Baltimore, Mich., assignor to The Astatic Corporation, Conneaut,
Ohio, a corporation of Ohio

Application December 12, 1946, Serial No. 135,452

Term of patent 7 years

(Cl. D26—14)

To all whom it may concern:

Be it known that I, Joseph B. Federico, a citizen of the United States, residing at New Baltimore, in the county of Macomb and State of Michigan, have invented a new, original, and ornamental Design for Microphone or the like, of which the following is a specification, reference being had to the accompanying drawing, forming part thereof.

Figures 1 and 2 are a front elevation and a side elevation respectively, of a microphone or the like embodying my novel design. A base for use with the article of the invention is shown in dotted outline in Figure 2 for illustrative purposes only.

I claim:

The ornamental design for a microphone or the like, as shown and described.

JOSEPH B. FEDERICO.
